In Germany August 21, 1939

6 Claims. (Cl. 250—27.5)

The invention relates to gaseous discharge devices, and particularly to such devices permitting current to reverse its direction through the devices.

An object of the invention is to prevent the temperature of the control electrode from reaching too high a value.

Another object of the invention is to space the control electrode or grid as far from the main electrodes as possible.

A still further object of the invention is to limit the intersection of the discharge path of both directions of current flow to that of the intersections of two cones.

Other objects and advantages of the invention will be apparent from the following description and drawing, in which:

Figure 1 is a cross-sectional view through a preferred embodiment of the invention.

Figure 2 is a top view of a modification of the electrode structure of Figure 1.

The present invention in its specific form, relates to a gas-filled or vapor-filled electric discharge vessel equipped with two electrodes, each capable of functioning alternately as a cathode and as an anode, so that current can flow through the vessel in either direction. In addition to those two main electrodes, there are provided one or more control electrodes that have to control the time-instants at which the ignition takes place, so that it becomes feasible, for instance, to control in a simple manner with the aid of the discharge vessel in question, the mean value of an alternating current that is caused to flow through the vessel.

The accuracy of the current-controlling effect obtainable by means of such a discharge vessel depends largely on the accuracy with which the ignition can be produced at the desired instants. In view hereof, it is quite important to see to it that the temperature of the control grid will not become too high, for in the case of a too high grid-temperature, thermionic emission by the control grid would interfere in an undesired manner with the discharge phenomena in the tube. Aside from a measure which consists in properly choosing the material for and the design characteristics of the control electrode proper, there is another effective measure for preventing the grid temperature from exceeding a certain maximum value in a discharge vessel of the twin-cathode type that is being used as a current converter, and this measure consists in making the distances from the control grid to the main electrodes as large as possible. It has been found

that it is especially advantageous to place the control grid at a sufficiently large distance from the main-electrode member that has to function as an anode.

It is known from experience, however, that large electrode-distances lead to high firing-voltage values and to a strongly positive orientation of the ignition characteristic. Hence it is not always advantageous or recommendable to resort to the measure of using large electrode distances.

The present invention discloses how the difficulties just referred to can be avoided in a very simple manner. In accordance with this invention, the main and control electrodes of a gas-filled or vapor-filled electric discharge vessel which, equipped with at least one control electrode, will permit a flow of current in either direction, are so designed and so arranged with respect to one another, that for each one of the two directions of current flow, the discharge path is essentially a cone-shaped surface which intersects the cone-shaped surface that constitutes the discharge path for the other direction of current flow. The vertex of each cone-shaped surface is supposed to be located on one of the main electrodes, or, more specifically, on that portion of this electrode which constitutes the cathode for the discharges taking place along the surface in question, while the base of the surface is located on the other main electrode, or, more specifically, on that portion of this electrode which constitutes the anode for said discharge.

In order to show more clearly how the present invention can find application in practice, reference will be made in this description from now on to the example of the application illustrated on the drawing. The latter shows a controllable discharge device of the twin-cathode type, whose vessel 1 is made of metal. It is obvious, however, that the device could be provided equally as well with a vessel made of insulating material.

Inside the vessel are mounted the two main electrodes, and the control electrode. The first main electrode 2 consists of a cathode member 3 and an anode member 4. Similarly, the second main electrode 5 consists of a cathode member 6 and an anode member 7. The anodes may be in the form of solid annulus strips, or they may be 50 ribbons of wire gauze which are standing on edge in the direction of the discharge.

The cathode members may be a heater wire, preferably covered with an electron-emitting oxide coating. The lead-in wires for the electrodes and the exhaust tube 8, are sealed by

fusion in plug-shaped glass bodies 9 and 10. The control grid 11 has several openings, two of which, designated by 12 and 13, are visible on the drawing. The latter shows clearly the peculiar arrangement of the electrodes. The dotted line 14 gives an approximate indication of the path following by a discharge taking place between cathode member 3 and anode member 7. This discharge essentially follows the surface of a cone, whose generatrix is the dotted line 14. The discharge in the opposite direction essentially follows the surface of a cone whose generatrix is the dotted line 15.

In place of the annulus for the anode in Figure 1, the anode portion may be segments, such as 20, 21, 22, 23, 24 and 25 on the conductive base 26. The location of these segments is determined by the place of impact of the conical discharge after passing through the openings 12.

It is readily seen from the drawing that by adopting an arrangement in accordance with the present invention, it becomes feasible to mount the anode members close to the grid openings, which are preferably located on a circle, and to keep, at the same time, the cathode members at a safe distance from these openings.

In other words, it becomes feasible to lower considerably the temperature of the grid without making the distance between anode and grid so large that the ignition voltage would be increased in an undesirable manner, and without incurring the other disadvantages generally encountered when the distance between anode and grid is made relatively large. Consequently, the ignition voltage of the discharge vessel will be low, the shape and orientation of the characteristic will be favorable, and the functioning of the vessel will be very accurate and, at the same time, very reliable, because the grid temperature is so low that emission by the grid will not occur.

It is especially advantageous to locate the centers of the grid openings on a circle, and to provide the anode in the form of an annulus, as has been done in the case of the example of application shown on the drawing. At the same time, a shield 16, 17 can be placed between the cathode member and the anode member of each main electrode, in order that the emissivity of the cathode will not be affected by the persistent fluctuations in anode temperature which fluctuations are due to the alternating character of the loading conditions.

The shape adopted for the anodes used in the discharge vessel, shown on the drawing, is also advantageous from the standpoint of heat removal. The controlling effect of the anode members 4 and 7, originates on the ring-shaped portions of these members which are very close to the grid openings. On the other hand, the discharge, which is the source of the generated heat, is free to spread out immediately and cover surface portions of the anode members, which are located at greater distances from the grid openings, and which, for this reason, will have a less dangerous influence on the grid temperature. Moreover, the heat absorbed by the anode from the discharge, will be rapidly transferred to the long external outer wall of the anode so that, because of the large surface area of this wall, said heat can readily flow off into the surrounding space in the form of radiant energy.

The distances between the various electrodes must be chosen depending on the conditions under which the vessel must operate, that is, depending on the magnitude of the voltages and

currents. In general, it will be advantageous to make the distance between the cathode member of each main electrode and the grid, from three to five times as large as the distance between the anode member of each main electrode and the grid.

When the discharge vessel in question is used in practice, it is often observed, although sometimes not until after the vessel has been operating for a considerable length of time, that in passing through the control grid, the discharge displays a certain preference for certain grid openings, insofar as it will pass almost exclusively through these particular openings, and not through the others. In order to suppress this tendency, it will be advantageous to shape and to arrange the anode members of the main electrodes in such a manner as to make that the pulling effect of each anode, with respect to a given group of grid openings, will be stronger than the pulling effect of the same anode with respect to the other grid openings.

This can be done in a very simple manner by providing, for instance, the anode members 4 and 7, not in the form of full rings, as in Figure 1, but in the form of ring segments, as in Figure 2. These ring segments are mounted in such positions that the anode member of the first main electrode will be located close to one group of grid openings, while the anode member of the second main electrode will be located close to another group of grid openings. The grid member 11 may have six openings for the six segments disclosed in Figure 2, and another six openings for the segments of the other anode portion, whose segments would be 30° displaced from the segments of the first anode portion. Various other arrangements may be utilized, such as having an anode portion on one semi-circle on one electrode, and on the other semi-circle on the other electrode.

These constructions just described will have the consequence that when the discharge takes place in one direction, it will always pass through the first group of grid openings, while a discharge taking place in the opposite direction will always pass through the second group of grid openings. It has been found that when this measure is taken, the life of the discharge vessel will be lengthened, while its controlling characteristics will be improved.

I claim:

1. A discharge device having an envelope containing two composite main electrodes, each having an anode portion and a cathode portion, the cathode portion having a central position and the anode portion in annular relation with said cathode portion, and a single control electrode intermediate said main electrodes.

2. A discharge device having an envelope containing two composite main electrodes, each having an anode portion and a cathode portion, the cathode portion having a central position and the anode portion in annular relation with said cathode portion, and a single control electrode intermediate said main electrodes, said control electrode comprising a plate with openings arranged in an annular path.

3. A discharge device comprising an envelope having a cathode located in a central portion at one end of the envelope, an annular anode at the other end of the envelope, and an intermediate control electrode with annularly arranged openings therein whereby the discharge path

from said cathode to said anode is substantially in the form of a cone.

4. A discharge device comprising an envelope containing two composite main electrodes, each having a central cathode portion and an annular anode portion surrounding said cathode portion whereby the discharge path from the cathode portion of one electrode to the anode portion of the other electrode is in the shape of a cone, and a control electrode intermediate said main electrodes and having discharge openings at the intersection of said discharge path cones.

5. A discharge device having an envelope containing two composite main electrodes, each having an anode portion and a cathode portion, the

10 cathode portion having a central position and the anode portion in annular relation with said cathode portion, and a heat shield intermediate the cathode and anode portions of each electrode.

6. A composite electrode for discharge devices, comprising a central cathode coil, a conducting base connected to one end of said coil, a connection to the other end of said coil passing through said base, insulation between said connection and said base, a heat shield arranged around said coil and an annularly shaped anode portion around said shield and coil on said base.

ADALBERT ETZRODT.
